UNITED STATES PATENT OFFICE

JOHN E. KELLEY, OF BANGOR, MAINE

HOLDER

Application filed May 28, 1930. Serial No. 456,411.

This invention relates to holders for maintaining articles or members, such as the trunk of a Christmas tree, in upright relation.

Among the objects of the invention may be noted the provision of a readily assembled device for holding a member, such as the trunk of a Christmas tree, in upright or vertical position from a horizontal surface such as a floor; the provision of a holder of the above character which is constructed of duplicate parts and capable of assembly or disassembly at will; the provision or base for upright members which is knock-down in character, and which is made up of component parts which may be nested for shipment or when not in use; the provision of a holder of the above character made up of duplicate parts, each having attaching means supplemental to attaching means arranged in an adjacent part, thus necessitating no extraneous fastening means upon assembly thereof; and the provision of a simple, durable and inexpensive holder which forms a stable support for an upright or substantially vertical member or article.

Other objects will be in part obvious from the annexed drawing and in part indicated from the following analysis of this invention, in which reference is made to the accompanying drawing illustrating an embodiment of my idea.

In the drawing—

Fig. 1 is a perspective view of an assembled holder of my invention;

Fig. 2 is a perspective view of the disassembled holder, the parts thereof being arranged for shipment or storage;

Fig. 3 is a perspective view of a modified form of holder;

Fig. 4 is a separated detail of certain of the parts of the holder shown in Fig. 3.

Referring now to the drawing, the holder as illustrated in Figs. 1 and 2 is composed of four oblong arm members 10, preferably of wood, which are machined or cut so as to

be duplicate or identical in character. Each member is provided with a pocket 11 preferably in the form of a dove-tail groove, which is disposed along a wall thereof and between the relatively short socket wall portion 12, 50 and a relatively extended brace portion 13. At the ends of each member and adjoining the socket wall portion 12, there is formed a tenon 14, preferably in the form of a dove-tail tongue. The pockets 11 and tongues 14 55 extend in a vertical plane when the holder is assembled or set up.

By the above described arrangement, the arm members 10 are arranged at right angles to each other with their brace portions extending outwardly, and the tongues 14 are slidably inter-engaged in the pockets 11. The bottom edges of the arms lie flush on the floor surface, and the relatively extended brace portions 13 of the arm form an extended bearing or brace. By reference to Fig. 1, the wall portions 12 of each of the arms are brought into adjacent relation and form a socket for the member or article to be held in upright position. Any inclination of 70 the article supported in the socket from a vertical position causes the contacting faces of the tenons or tongues 14 and pockets 11 to bind on each other. Consequently, the faces of the said pockets and tenons are restrained 75 from relative slipping, and the holder is maintained in an operative assembled condition when any article is held upright within the socket. Upon removal of the member or article from the socket, the binding pressure 80 is relieved and the tenons of the arms are freely slidable from the pockets of the co-operating arms whereby to permit ready disassembly.

In the modified form of holder as illustrated in Figs. 3 and 4, there is shown a holder of sheet metal, preferably steel. In this modified form, four duplicate arm members 20 are provided, each fabricated from a single blank of sheet metal and bent or folded lon- 85 90

gitudinally thereof to form leaves or sides 21, 22 and a connecting neck 23. Intermediate the relatively extended brace portions 24 and socket wall portions 25 of each arm, the sides are spaced apart whereby to form a groove or pocket 26. Otherwise the sides 21, 22 are in contacting relation whereby to provide good reinforcement. Across one of the sides, such as the side 22 of each arm, is provided a slot 28 in communication with the pocket 26 for the purpose to be hereinafter stated.

At one end of the arm members 20 and adjacent the socket wall portion 25 thereof, I provide a tenon or tongue 30, the same comprising extensions from the sides 21, 22 of the arms, which are bent or flanged outwardly to extend in a plane normal to the longitudinal plane of the arms 20. A connecting web 31 between the tongue extensions 30 and the arm 20 provides a rigid link between said parts. While each of the tongues 30 are shown as formed of two flanged extensions, it will be understood that the tongue may be formed by a single flanged extension extending from one or the other of the sides 21, 22.

The connecting neck 23 between the sides 21, 22 of the arm members is preferably cut away along the pocket 26 to form an open mouth permitting entry of the tongue 30 in said pocket. The web 31, upon assembly of the parts, is adapted to enter the groove 28, which latter forms a guideway or track which aids in the proper seating of the tongue in the pocket. It will be evident that the tongue 30 may be engaged in the pocket 26 thru the bottom thereof as well as thru the pocket mouth as described.

When desired, a reinforcing rib 23 may be formed in the wall 21 of each arm 20 adjacent the pocket, whereby to provide a reinforcement for the arm at the pocket portions thereof.

As in the holder illustrated in Figs. 1 and 2, the arms 20 are adapted to be assembled by engaging the tongues 30 in the pockets 26, whereby the socket wall portions 25 are disposed in adjacent relation to form a socket opening for an article such as the trunk of a tree. In a similar manner, any inclination of this article from a vertical or upright position causes the contacting surfaces of the tenons or tongues 30 and pockets 26 to bind on each other, and results in the holder being maintained in an operative assembly under all conditions of use. Upon removal of the article from the socket, the tongues 30 may be slid from engagement with the pockets 26 and the arms 20 nested for storage or the like.

It will be seen that the several objects of the invention are achieved and other advantageous results attained. As many changes could be made in carrying out the above invention, without departing from the scope

thereof, it is intended that all matter contained in the accompanying drawing shall be interpreted as illustrative and not in a limiting sense.

I claim:

1. A device for holding an article in upright position comprising a plurality of duplicate members each having means at one end permitting and causing attachment with another of said members, and in one side attaching means complementary to said first-named means and located between a relatively short socket wall portion and a longer brace portion of said member, both of said means being vertically arranged when the device is in use and operatively related for slidable engagement with each other, the arrangement being such that any inclination of the article from a vertical position causes both said means to assume a non-slipping relation with respect to each other, both said means being otherwise freely disengageable.

2. A device for holding an article in upright position comprising a plurality of duplicate members, each having an integral extension at one end thereof, and in one side a pocket located between a relatively short socket wall portion and a longer brace portion of said member, the extensions and pockets being slidably interengaged and vertically arranged when the holder is in use, the arrangement being such that any inclination of the supported article from a vertical position causes the extension to more tightly engage in the pockets, whereby to prevent slipping of the extension within the pockets and to maintain the device in operative relation under all conditions of use, the extensions being otherwise freely slidable out of the pockets.

3. A holder of the character stated, composed of four duplicate oblong flat-sided arms, each having at one end a dovetail tongue, and in one side a dovetail groove, spaced from the tongue and formed to receive and be separably interlocked with the tongue of another arm, the tongue and groove extending crosswise of the arm, the arrangement being such that the tongues and grooves of the several arms may be interlocked to form a holder, adapted to have an extended bearing on a floor, and including a central four-sided socket, and arm portions projecting outwardly in different directions from the corner portions of the socket, the tongues being slidable into and out of the grooves, so that the holder may be erected for use, and knocked down for storage and shipment.

4. A socketed and braced holder composed of a plurality of duplicate oblong members, each having a tenon at one end and in one side a pocket located between a relatively short socket wall portion and a longer brace portion of said member, the tenons and pock-

ets being slidably interengaged and vertically arranged when the holder is in use, the arrangement being such that any inclination of a supported article from a vertical position causes the contacting faces of the tenons and pockets to bind on each other and prevent slipping of the pocket faces on the tenon faces so that the holder is maintained in an operative condition under all conditions of use, the tenons being freely slidable out of the pockets when no binding pressure is exerted thereon.

5 Signed at Bangor, Maine, this 24th day
10 of May, 1930.
